UNITED STATES PATENT OFFICE

SIMON E. SCHROEDER, OF MINIER, ILLINOIS

WASHING-MACHINE-AGITATOR MECHANISM

Application filed December 24, 1928. Serial No. 328,216.

This invention relates to improvements in washing machine agitators and more particularly to those positioned near the bottom of a tub and driven by an oscillating shaft 5 rising therefrom.

Heretofore it has been found necessary to make the agitator, or the portion of it covering the oscillating shaft, of a height sufficient to stand above the level of the water 10 within the tub to prevent any leakage of water into the mechanism of that portion and also to prevent any oil or grease working out of the shaft bearings and into the water where it would come in contact with the 15 clothes to be washed. Because of this condition, an agitator of such height is cumbersome and unnecessarily occupies space within the tub that might otherwise be used for water and clothes, thereby decreasing the capacity of a given size of tub.

The chief object of this invention is to provide an agitator mechanism of such construction that it may lie completely below the surface of the liquid within the container, 25 and yet will prevent the liquid from leaking out of the tub through any part of the agitator mechanism.

Another object of the invention is to construct the mechanism of the agitator in such 30 a way that no oil or grease used in the mechanism can exude from any point into the liquid in the container.

A further object is to provide a novel liquid-tight connection between the oscillating 35 portion and the stationary portion of the agitator mechanism, which connection is capable of flexing or twisting to accommodate the oscillatory movements.

Other objects and advantages from the 40 invention will become apparent from the following detailed description taken in connection with the accompanying drawings, in which:

Figure 1 is a plan view of a washing machine embodying the features of my invention.

Fig. 2 is a fragmentary vertical section taken on the line 2-2 of Fig. 1.

Fig. 3 is a vertical section of the machine 50 taken on the line 3-3 of Fig. 1.

Fig. 4 is a horizontal section taken on the line 4-4 of Fig. 3.

While the invention is susceptible of various modifications and alternative constructions, I have shown in the drawings and will 55 herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawings, the exemplary 65 embodiment of the invention comprises a base frame 10 on which is supported a tub or container having side walls 11 and bottom 12. Within the container and projecting from the bottom 12 is an agitator generally indicated by 13 and lying completely below 70 the water level shown in Fig. 3.

The exemplary means herein shown for driving the agitator is constructed as follows: Below the container there is mounted a motor 20 to the shaft of which a worm 21 75 is rigidly connected. The worm meshes with a worm wheel 22 mounted on a vertical shaft 23. To the top of the shaft 23, a crank arm 24 is keyed. On the crank arm 24 there is a crank pin 25 to which a bar 26 is pivoted. On 80 the end of the bar 26 opposite to that pivoted on the crank pin 25, a rack 27 is cut. Abutting the bar 26 is a roller 28 suspended by a crank pin 29 on a crank arm 30, the latter being pivoted at 31. A spring 32 is attached 85 to bar 26 and holds it in contact with the roller 28. To the upper end of crank pin 29 a link 35 is attached. The opposite end of link 35 is attached to a crank pin 36 on a crank arm 37 the latter being keyed to the 90 lower end of a vertical shaft 38. On the upper end of shaft 38 is a handle 39.

The rack 27 meshes with a pinion 42 fixed to the lower end of a vertical shaft 43, the latter projecting up through the bottom 12 of 95 the container. Surrounding the shaft 43 is a flange 44 resting on the bottom 12. Interposed between the flange 44 and the bottom 12 is a gasket 45 so that when the flange 44 is attached to the bottom 12 by bolts or the like, a 100

liquid-tight connection is formed therebetween. The flange 44 has an upwardly turned annular collar 46 and positioned within the collar 46 is a tubular sleeve 47, the latter supporting, at its end, bearings 48 and 49 for the shaft 43. A head 50 is rigidly attached to the upper end of shaft 43, said head having a downwardly turned annular collar 51.

- 10 To prevent leakage of liquid from the container, a flexible tubular member 55 has one of its ends slipped over the collar 46 of the flange 44 and fixed thereto by a clamp 56. The upper end of member 55 is slipped over the collar 51 of the head 50 and fixed thereto by a clamp 57. These clamps 56 and 57 may be similar to a standard hose clamp. The tubular member 55 may be made of rubber, or fabric and rubber-like hose, or other suitable material.
- 15 20 The agitator 13 comprises a tubular portion 60 closed at its upper end. This portion 60 forms a driving connection with the head 50 by any well-known means, the particular means shown here being complementary hexagonal portions formed on the tubular portion 60 and the head 50. The tubular portion 60 extends downwardly externally of the member 55 to a flange 61, the latter being seated upon the flange 44. Formed integrally 25 with the tubular portion 60 and the flange 61 are vanes 62.

25 The operation of the machine is as follows: Assume the motor 20 to be running and the parts of the machine in the positions shown in the drawings. The worm 21, meshing with the worm-wheel 22, causes the latter to rotate. The wheel 22 and the crank arm 24 being mounted on the shaft 23, the arm 24 rotates with the wheel 22 and bar 26 connected to 40 crank pin 25 is reciprocated. With the roller 28 in the position shown, rack 27 is held in mesh with pinion 42, the latter being oscillated thereby as well as the shaft 43 to which the pinion 42 is keyed.

- 45 50 The oscillation of the shaft 43 causes the agitator 13 to oscillate by means of the rigid attachment of the head 50 on the shaft 43 and the driving connection between the tubular portion 60 and the head 50. Flange 44 being fixed to the bottom 12 does not oscillate while the head 50 does so. The flexible tubular member 55 being fixed to these two parts, or portions thereof, is twisted by the oscillatory motion but at all times forms a seal around the shaft to prevent leakage.

55 60 To stop the motion of the agitator 13 without shutting off the motor 20, handle 39 is turned in either direction causing a rotation of the shaft 38 and the crank arm 37. Through the link 35, crank arm 30 is then rotated and roller 28 moves away from the pinion 42. Spring 32 holding the bar 26 in contact with roller 28 causes rack 27 to be moved out of mesh with pinion 42 and the latter together with the agitator 13 is per-

mitted to come to a stop. It is apparent that reverse movement of the handle 39 will throw the rack 27 back in mesh with pinion 42 and the agitator 13 will again oscillate.

65 70 It is evident from the above description that I have provided an agitator that may lie completely below the surface of the liquid in the container without any leakage through any part of the agitator mechanism, and in which a flexible liquid-tight connection is 75 formed between the oscillating portion and the stationary portion of the agitator mechanism.

I claim as my invention:

1. In a washing machine having an agitating mechanism projecting from the bottom of the tub, the combination of stationary means mounted on the bottom of the tub, oscillating means projecting through said stationary means, an agitator mounted on said oscillating means and driven thereby, and a flexible liquid-tight connection between said stationary means and said oscillating means. 80

85 2. In a washing machine having an agitating mechanism projecting from the bottom of the tub, the combination of stationary means mounted on the bottom of the tub and forming a liquid-tight joint therewith, an oscillating shaft projecting through the bottom of the tub and said stationary means and having a head mounted thereon, an agitator mounted on the head of said shaft and forming a driving connection therewith, and a flexible tube connecting said stationary means and said head and forming a liquid-tight connection therebetween. 90

95 100 3. In a washing machine having an agitating mechanism projecting from the bottom of the tub, the combination of an oscillating shaft projecting through the bottom of the tub, a flange rigidly mounted on the bottom of the tub and forming a watertight connection therewith, said flange having an upturned collar coaxial with said shaft, a head mounted on the top of said shaft and having a downwardly extending collar coaxial with said shaft, an agitator mounted on said head and having a driving connection therewith, and a flexible tube connecting the upturned collar of said flange and the collar of said 110 head to form a liquid-tight connection therebetween. 115

120 125 4. In a washing machine having an agitating mechanism projecting from the bottom of the tub, the combination of an oscillating shaft extending upwardly through the bottom of the tub, a stationary flange mounted on the bottom of the tub to form a liquid-tight connection therewith, an upturned collar on said flange and coaxial with said shaft, a tubular sleeve rigidly mounted within said flange and extending along the shaft, two bearings mounted within the sleeve for supporting said shaft, a head mounted on the top of said shaft to oscillate therewith, a down- 130

turned collar on said head and coaxial with said shaft, a flexible tube surrounding the collar on the flange and the collar on the head to form a liquid-tight connection therebetween, and an agitator having a central tubular portion closed at its upper end and enclosing said head and sleeve, the upper part of said tubular portion engaging with said head to form a driving connection therebetween, and the lower part of said agitator being seated upon said flange.

5 5. In an oscillating agitator mechanism for a washing machine in which the agitator projects from the bottom of the tub, the combination of oscillating means operable to oscillate the agitator, stationary means adapted to support said oscillating means, and a flexible liquid-tight connection between said oscillating means and said stationary means.

20 6. In an oscillating agitator mechanism for a washing machine in which the agitator projects from the bottom of the tub, the combination of an oscillating shaft projecting into the tub through the bottom thereof, a stationary flange rigid with the bottom of the tub and surrounding said shaft, means on the top of said shaft adapted to form a driving connection with the agitator, and a flexible tube connecting said flange and said means whereby to form a liquid-tight connection therebetween.

25 7. In an oscillating agitator mechanism for a washing machine in which the agitator projects from the bottom of the tub, the combination of a vertical oscillating shaft projecting through the bottom of the tub, a flange surrounding the shaft at the point where it projects through the bottom of the tub and rigidly secured to the bottom of the tub, a flexible tube surrounding the shaft above the flange and tightly secured to said flange, a head closing the upper end of said tube and rigidly secured to the shaft whereby said head may be oscillated by said shaft, said head adapted to form a driving connection with the agitator, and said flange, said tube and said head arranged to form a seal around the shaft to prevent leakage.

50 8. In an oscillating agitator mechanism for a washing machine in which the agitator projects from the bottom of the tub, the combination of a vertical oscillating shaft projecting through the bottom of the tub, a stationary flange surrounding said shaft at the point where said shaft passes through the bottom of the tub, said flange having a liquid-tight connection with the bottom of the tub, a head at the top of said shaft and rigidly connected thereto, said head being constructed to form a driving connection with the agitator, and a flexible tube the ends of which are rigidly connected to the flange and the head respectively so that a liquid-tight housing formed by said flange, said tube and said cap surrounds said shaft to prevent leakage of liquid

from the tub through the agitator mechanism.

9. In an oscillating agitator mechanism for a washing machine in which the agitator projects from the bottom of the tub, the combination of a vertical oscillating shaft projecting through the bottom of the tub, a stationary flange secured to the bottom of the tub and forming a liquid-tight connection therewith, said flange having a central aperture through which said shaft projects and an upturned annular portion, a head mounted on top of said shaft and so shaped as to form a driving connection with the agitator, said head having a downturned annular portion, and a flexible tube the ends of which are snugly fitted over the annular portions of said flange and said head respectively whereby to form a liquid-tight connection therebetween.

70 10. In an oscillating agitator mechanism for a washing machine in which the agitator projects from the bottom of the tub, the combination of an oscillating shaft projecting into the tub through the bottom thereof, a centrally apertured flange rigidly secured to the bottom of the tub and surrounding said shaft, said flange having a seating portion on which the agitator is rotatively supported and an upwardly extending annular portion, a housing rigidly secured within the aperture of said flange and extending therefrom, said housing supporting two bearings for said shaft, a head mounted on the top of said shaft and rigidly secured thereto, said head forming a driving connection with the agitator and having a downwardly extending annular portion surrounding said housing, and a flexible tube the ends of which are rigidly secured to the annular portions of said flange and said head respectively whereby to form a liquid-tight connection therebetween.

80 11. A machine of the character described comprising, in combination, a container, an agitator therein, oscillatory driving means for said agitator, and a flexible sealing enclosure for said driving means.

90 12. A machine of the character described comprising, in combination, a container, an agitator therein, driving means for said agitator including an oscillatory shaft extending into said container, and a flexible tubular sealing enclosure surrounding said shaft.

100 13. A machine of the character described comprising, in combination, a container, an agitator therein, oscillatory driving means including a shaft, a stationary part through which said shaft projects, and a tubular sealing element surrounding said shaft and having its ends fixed to said driving means and to said stationary part, said sealing element being capable of twisting to follow the oscillatory movement of said driving means.

14. A machine of the character described comprising, in combination, a container, an agitator therein, an oscillatory shaft, a stationary part sealed to said container and through which said shaft projects, a head on said shaft forming a driving connection with said agitator, and a tubular sealing element surrounding said shaft and having its ends sealed to said head and said stationary part, said sealing element being capable of being twisted to follow the oscillatory movement of said head.

15. A machine of the character described comprising, in combination, a container, agitating means therein, oscillatory driving means adapted to drive said agitating means, and a flexible sealing element having its ends fixed to said container and to one of said means.

16. A machine of the character described comprising, in combination, a container, a shaft projecting into said container, said shaft and container being arranged to have a relative oscillatory movement about the axis of said shaft, and a flexible tubular sealing means having its ends fixed respectively to said container and said shaft, said sealing means being capable of twisting to follow said oscillatory movement.

30 In testimony whereof, I have hereunto affixed my signature.

SIMON E. SCHROEDER.
